TO GREENLEE BROS. & COMPANY, OF ROCKFORD, ILLINOIS, A CORPORATION OF
ILLINOIS.

TIE-GAINING MACHINE.

1,141,887.

Specification of Letters Patent.

Patented June 1, 1915.

Application filed April 1, 1913. Serial No. 758,172.

To all whom it may concern:

Be it known that we, GEORGE C. PURDY and DANIEL W. EDWARDS, citizens of the United States, residing at Rockford, in the county of Winnebago and State of Illinois, have invented certain new and useful Improvements in Tie-Gaining Machines, of which the following is a specification.

This invention relates to wood gaining machines, and more particularly to those adapted to gain railroad-ties.

An object of the invention is to provide a machine which will gain all ties uniformly regardless of the varying irregularities thereof, that is, one in which the gaining cutters will gain the tie throughout the length of said cutters so that the gained portions shall be of a uniform predetermined depth. This object is accomplished by providing novel equalizing supports adapted to carry the tie while it is being gained.

A further object is to provide means for indicating the positions of said equalizing supports relative to the gaining tools, and also actuating means for positioning the supports in view of such indication, to gain at a predetermined uniform depth.

A further object is to construct improved devices adapted to coöperate in the gaining of the tie to secure a center of operation at each gained portion, such devices comprising tie carrying means and cushioned means for holding the tie in an operative position.

A further object is to construct a tie gaining machine in which the coöperating means acting upon one end of a tie, are adapted to be carried upon an adjustable carriage which may be moved over the bed of the machine transversely to the feed of the tie through the machine.

In the accompanying drawings, Figure 1 is a plan view of our improved gaining machine. Fig. 2 is a side elevation of the machine looking at the feed entrance of the machine, the tie feed conveyors and equalizing control levers being omitted. Fig. 3 is an end elevation of the machine illustrating the control end. Fig. 4 is a vertical section on the line 4—4 of Fig. 1. Fig. 5 is a section on the line 5—5 of Fig. 1, the adjustable carriage having been moved toward the fixed carriage, and illustrating the positions of the equalizing supports in relation to an irregular tie. Fig. 6 is a fragmentary side elevation of the adjustable carriage as shown

at Fig. 2. Fig. 7 is a diagrammatic view illustrating the control of the equalizing support as shown in Fig. 6. Fig. 8 is an end elevation of the drive means only, at the drive end of the machine. Fig. 9 is a vertical section on the line 9—9 of Fig. 2, through the adjustable carriage. Fig. 10 is a section on the line 10—10 of Fig. 2, of the air cushioned holding shoe, showing it in a lowered inoperative position.

The rectangular base 11 of the machine has formed longitudinally thereof, two parallel tracks 12 upon which are mounted two carriage or supporting frames 13 and 14, the frame 14 being fixedly secured thereto. The movable frame or carriage 13 is guided in position by the gib-plates 12' and is fed along the base by operating the hand-wheel 15, which is journaled in the supporting-bracket 16 bolted to the base and carries a spur-pinion 17 driving with the spur-gear 18 journaled in bracket 16, said spur-gear 18 being keyed to the screw-shaft 19 that drives in engagement with the screw-bracket 20 bolted to carriage 13.

The two frames 13 and 14 and the several devices carried thereby are of a like construction, except for certain drive means having connection with frame 14, so therefore we will describe the construction of but one frame broadly speaking, and the reference numerals as applied thereto will refer to the like parts on both frames.

The frames 13 and 14 are each formed with a cutter casing 21 and laterally extending journal supports 22, frame 13 having an extending journal support 23 and frame 14 having a journal support 24. Suitable means may be employed to operate the gaining cutters and tie conveyors, having here shown a main drive-shaft 25 journaled in supports 23 and 26, which drives a counter-shaft 27 through means of the loose and driving pulley belt connections 28, said counter-shaft 27 driving a stud-shaft 29 by spur-pinion and gear 30, and the stud-shaft 29 driving the conveyer-shaft 31 journaled in supports 20, 22 and 24, through means of spur-pinion and gear 32. Journal bearings 33 carried by the frames are formed with supports 34 adjustable with the frames and carry a conveyer-shaft 35. Following more particularly the adjustable carriage 13, sprocket-wheels 36 are mounted on conveyer-shafts 31 and 35, being keyed thereto, and

the endless chain 37 in driving connection with said sprocket-wheels, is carried during its upper horizontal travel in the guide-rail 38 which is bolted to the frame and has an extension-guide 39 bolted thereto at the tie entrance of the machine, the guide and guide-plate forming also, a rail upon which the ties are conveyed through a portion of their travel through the machine. Pivoted extension dogs 40 are carried by chain 37, the dogs having a front and rear pivotal support and have a head 41 adapted to engage a tie. A cutter-head shaft 43 is journaled in the journal-bearings 44 bolted to the top of the cutter casing and has fixedly secured thereon a suitable form of cutting-head 45 disposed in the opening 46 in the top of said casing. A pulley 47 fixed on one end of said shaft is driven through a belt drive by the drive-pulley 42, keyed to the drive-shaft 25. A shaving guide 48 is pivotally mounted to the feed side of the cutter and is held yieldingly against a tie passing thereover by the spring 49, in order to guide all shavings being thrown thereagainst, into the cutter casing and out of the shaving discharge conduits 50. An equalizing support is formed of two parallel supporting bars 51 bolted together by the cross-bars 52. Supporting links 53 have a pivotal connection with each cross-bar at 54 and a bifurcated end having a pivotal connection 55 with the eccentric-ring levers 56. The eccentric-ring levers are mounted on eccentrics 57 fixedly secured to shaft 58 which is supported in bearings 59 in the frame. Brackets 60 hold the links 53 slidable and against lateral displacement. Adjusting levers 61 are pivotally mounted on the stands 62 and have connection through rods 63 with crank-arms 64 fixed with the eccentric-shafts 58, the rod 63 connecting with the crank-arm on the adjustable carriage 13, having a longitudinal adjustment to allow for movement of the carriage. Rods 65 have a fixed connection with each equalizing support at 54 and extend outward being connected with the rods 66 which rock the indicator fingers 67 carried by stands 62, thereby registering when the equalizing supports have been pivoted, the angle of such pivoted position. Bolted to the ends of each frame are standards 68 which carry rods 69 forming an overhead support. Secured to the standard carried by frame 14 is the end guide-plate 70 carried by a bracket 71 adjustable in the ways 72, said guide-plate being set to center the tie in relation to the cutting heads.

Means are carried above each cutting head for holding the ties in position during the gaining operation. A supporting bracket 73 is bolted to the rods 69 and has upstanding ears which carry pivotally by pin 74, the cylinder 75 having a piston-rod 76 and piston 77 (Fig. 10), said cylinder having open-

ings 78, and 79 at the top and bottom thereof, respectively. Piston-rod 76 is provided with an adjustable stop 80 at its upper end, and has a pivotal connection 81 at its lower end with the tie shoe 82. Tie shoe 82 has at its entrance end, an oblique guide-plate 83, and a suitable lubricant receptacle 84 communicating with the guide face, said receptacle carrying a solution adapted to dissolve and free said face from pitch or the like accumulating thereon from contact with ties. Tie-shoe 82 is supported by bracket 73 through the parallel connection comprising upper and lower links 85 and 86 respectively, connected by parallel links 87, and the guide-links 88. This holding means is shown in its inoperative position in Fig. 10 and a tie being fed through the machine will contact the guide-plate 83, raise the shoe to a position as shown in the other views thereof, the air above the piston 77 passing out of opening 78, the weight of the shoe being sufficient to hold the tie during the gaining operation, and upon the tie being conveyed away therefrom, the shoe will drop to the inoperative position, but the drop will be a slow one as the fall will be cushioned by the slow escape of air from the lower hole 79. The adjustable stop 80 limits the downward movement of the shoes.

95

Suitable conveyers 89 are shown mounted on shaft 35, driven thereby, and adapted to carry ties to the machine, and discharge conveyers 90 are similarly driven by shaft 31 and discharge the ties. When it is desired, the gaining machine may be placed adjacent a tie-boring machine in such a manner that the ties continue their passage from the gaining machine directly to the boring machine to be bored in the gained portions of the tie.

The main drive-shaft 25 is to be driven at a high rate of speed in order to rotate cutter-heads 45 at the desired speed, while it will be seen that the drive through the belt and gear connections to the conveyer drive-shaft 31 is entirely step down, so as to rotate said shaft 31 slowly and move the tie conveying means at the right speed.

Following the passage of a tie through the machine regardless of the action of the equalizing supports and control therefor, a tie is carried by conveyers 89 to the extension guides 39 when it is engaged by dogs 40 and carried along the guide-rails 38 and onto the equalizing supports 51, which are carried above the level of said guide-rails, are then engaged by the cushioned holding means overhead, the action of which has been described above, are gained by the revolving cutter-heads 45, and are then conveyed off of the equalizing supports and discharged from the machine.

It will be seen in the case of a set rotary cutter and a fixed tie carrying rail, that

120

125

130

when a tie of an irregular shape is gained, very often the cutter will not gain a surface throughout the longitudinal length of the cutter because of such irregularity in the tie, 5 but will cut deep on one end of the cutter and not contact the tie with its other end. By providing our equalizing supports this defect is overcome, and in Fig. 5 we have illustrated a tie irregular in shape showing 10 the action of said equalizing-supports.

Illustrating a particular case, assume a machine of the set cutter and fixed tie rail type, and the cutters set to gain a portion $\frac{1}{4}$ inch in depth, that is, the cutter face is set $\frac{1}{4}$ 15 above the rail. A tie is conveyed thereover, being irregular in shape so that the proposed surface to be gained is not parallel with the cutter face. A cut $\frac{1}{4}$ inch deep is taken, but it only covers one-half the 20 width of the cutter because of the incline to the surface of the proposed gained portion of the tie. With an equalizing support, in the place of said fixed tie-rail, and the cutter set in the same position and cutting depth, 25 when a similar irregular tie is conveyed thereover, the equalizing support will pivot, dividing the irregular distance between each end of the cutter and the face of the tie, and lower the tie one-half this distance, thereby 30 gaining at the center portion of the cutter $\frac{1}{4}$ inch deep and throughout the length of the cutter to a varying depth resulting from said irregularity.

The indicator fingers 67 show at what angle the equalizing-supports are tilted, and if such irregularity of the tie is indicated to be so great that an entire cut will not be taken, the levers 61 are operated to lower the equalizing supports until the indicator 40 finger is within a predetermined point. It will be understood that as in the above illustrated case, levers 61 would be set for a cut $\frac{1}{4}$ inch and the indicator finger would have a certain range of movement corresponding 45 to irregularities of ties that would be gained the length of the cutter with this set position, and that said levers would be operated only when the indicator-fingers went beyond this limit.

50 In moving the adjustable carriage over the base by the hand-wheel 15 the several coacting instrumentalities operating upon that end of the tie, with the exception of the tie holding means indicator fingers and their 55 control levers which may be movable by loosening set-screws holding it fixed on rods 69, are moved bodily, thereby maintaining the relative position of one instrumentality to the other, and retaining a center of operation regardless of said movement of the carriage over the frame.

The vertical adjustment of the equalizing support could be accomplished by operating means of other constructions than that disclosed herein, for instance, means for auto-

matically raising or lowering the supports, without departing from the scope of our invention.

We claim as our invention.

1. A gaining machine comprising a gaining cutter, a rectangular frame surrounding the cutter, the ends of said frame being parallel with the axis of the cutter and being pivotally supported, the side members forming carrying rails along which an article 70 moves to be gained, and means for adjusting the position of the pivotal support of the frame relative to the cutter in order to vary the depth to which the article is to be gained.

2. In a machine of the character set forth, 80 a gaining cutter, a platform along which an article moves to the gaining cutter to be gained thereby, said platform being in a set relation to said cutter for obtaining a predetermined depth of gaining, and being 85 movable to vary said depth of gain, according to the angle of the article face relative to the cutting face of the gaining cutter, and means for adjusting the platform relatively to the cutter to vary said predetermined 90 depth of gain without affecting its movement by the article to be gained.

3. In a gaining machine, the combination 95 of gaining cutters and means for carrying an article to the gaining cutters, of movable supports adapted to carry an article when it is being gained, the supports being adapted to conform to the angle of an irregular face of the article to be gained and to adjust the article in relation to the cutters so that said 100 cutters will gain throughout the length of their cutting faces, means for indicating the angling of said supports, and means for moving each support for varying the depth of gain by independent operation of each of 105 the operable means.

4. In a tie gaining machine, the combination 110 of a gaining cutter mechanism for feeding ties in succession past said cutter and means positioned adjacent to said cutter for supporting the stock at each end of the cutter during the cutting operation, said means being movable by irregularities in the surface of the stock during the travel of the stock thereover to cause a cut which will 115 compensate for such irregularities to be produced.

5. In a tie gaining machine, the combination 120 of a gaining cutter mounted in stationary bearings, mechanism for feeding ties disposed adjacent the ends of said cutter for supporting the stock at each end of the cutter during the cutting operation, said means being adapted to conform to irregularities in the 125 surface of the stock traveling thereover, so that the differences in the stock at the ends of the cutter will be compensated for in the cut produced.

6. In a tie gaining machine, the combina- 130

tion of a gaining cutter, mechanism for feeding ties past said cutter by a continuous movement, and pivotally mounted means for supporting the stock adjacent the ends of the cutter during its travel, said means being movable on its pivotal axis by variations from a horizontal plane in the surface of the stock resting thereon, whereby a cut compensating in depth for such variations from the horizontal will be produced.

7. In a tie gaining machine, the combination of a gaining cutter, vertically movable means positioned adjacent to each end of said cutter for supporting the stock to be gained, mechanism for holding the stock against said means as it travels thereover, said means being movable to conform to the shape of the lower face of the stock supported thereby for the purpose of presenting the stock to the cutter so as to produce a cut which will compensate for irregularities in the surface of the stock.

8. In a tie gaining machine, the combination of a rotary cutter, a stock supporting member positioned at each end of said cutter, pivotally mounted means rigidly connecting said members, said members being movable about the pivotal axis of said connecting means to conform to irregularities in the stock supported thereby, means for feeding stock longitudinally of said members, and means for indicating the variation from a horizontal plane of said supporting members.

35 9. In a tie gaining machine, the combination of a cutter, means disposed at each end of said cutter for supporting the stock to be gained, said means being pivoted upon a horizontal axis intermediate the ends of the cutter and transverse to the longitudinal axis of said cutter, and means for varying the position of said pivotal axis with respect to the cutting plane of said cutter.

10. In a tie gaining machine, the combination of a cutter, means pivotally supported to tilt about an axis transverse to the cutter for supporting the stock to be gained at each end of said cutter, and means for varying the height of said pivotal support.

50 11. In a tie gaining machine, the combination of a cutter, means for supporting the stock to be gained, comprising a pair of rigidly connected members disposed respectively at each end of the cutter and pivotally supported intermediate the ends of the cutter, on an axis transverse to the cutter, and mechanism for adjusting the height of said pivotal support.

12. In a tie gaining machine, the combina-

tion of a plurality of cutters, means comprising members disposed at each end of each cutter for supporting the stock to be gained, means for pivotally supporting the members intermediate the ends of said cutter to permit a rocking movement of said stock-supporting means transversely of the longitudinal axis of the cutter, and means whereby the height of the supporting means adjacent each cutter may be adjusted.

13. In a tie gaining machine, the combination of a plurality of cutters, work supporting means comprising members disposed adjacent each end of each cutter, the members adjacent each cutter being pivotally supported intermediate the ends of their respective cutter upon an axis transverse to the cutter, means for indicating variations in height between the members at opposite ends of each cutter, and means whereby the members adjacent any cutter may be raised or lowered together irrespective of the position of the members adjacent any other cutter.

14. In a tie-gaining machine, the combination of a cutter mounted in stationary bearings, means for feeding stock past the cutter, a rigid stock supporting frame comprising elongated members disposed at opposite ends of the cutter to support the stock at the ends of the cutter during its travel past the cutter, means for pivotally supporting said frame between said members, and mechanism whereby said supporting pivots may be raised and lowered.

15. In a tie-gaining machine the combination of a stationarily mounted cutter, a frame comprising longitudinal stock supporting members positioned at the ends of the cutter and transverse connecting members pivotally supported intermediate their ends, to permit said frame to rock when irregular stock passes thereover, and means for raising and lowering said frame.

16. In a tie-gaining machine the combination of a cutter, a frame pivoted intermediate the ends of the cutter at the front and rear of said cutter and comprising parallel members positioned adjacent the ends of the cutter to support the stock during the cutting operation, and means for adjusting said frame vertically relative to the cutter.

In testimony whereof we have hereunto set our hands in presence of two subscribing witnesses.
